The ornamental design for a clip for a pacifier, as shown and described.

DESCRIPTION

FIG. 1 is a front view of a clip for a pacifier, according to this invention;

FIG. 2 is a rear view of the clip for a pacifier, as shown in FIG. 1;

FIG. 3 is a side view of the clip for a pacifier, as shown in FIG. 1;

FIG. 4 is a side view, opposite the side view as shown in FIG. 3, of the clip for a pacifier, as shown in FIG. 1;

FIG. 5 is a bottom view of the clip for a pacifier, as shown in FIG. 1; and,

FIG. 6 is a top view of the clip for a pacifier, as shown in FIG. 1.

FIG. 6

FIG. 1

FIG. 5

FIG. 3

FIG. 2

FIG. 4
